UNITED STATES PATENT OFFICE

164,777

ROSARY RING

William B. Kelly, Glendale, Calif.

Application June 18, 1951, Serial No. 15,591

Term of patent 7 years

(Cl. D45—10)

To all whom it may concern:

Be it known that I, William B. Kelly, a citizen of the United States, residing in the city of Glendale, county of Los Angeles, State of California, have invented a new, original, and ornamental Design for Rosary Ring, of which the following is a specification, reference being had to the accompanying drawing which forms a part thereof and in which drawing:

Fig. 1 is a front elevation of a rosary ring embodying my new design,

Fig. 2 is a top plan view of the ring shown in Fig. 1,

Fig. 3 is an elevation as viewed from the right hand side of Fig. 1,

Fig. 4 is an elevation as viewed from the left hand side of Fig. 1, and

Fig. 5 is a view in flat development illustrating the ornamented portion of the ring.

I claim:

The ornamental design for a rosary ring, substantially as shown.

WILLIAM B. KELLY.
